METHOD FOR SECONDARY RECOVERY
OF PETROLEUM

Robert J. Quance, Tulsa, Okla., assignor to Pan American Petroleum Corporation, Tulsa, Okla., a corporation of Delaware
No Drawing. Filed Apr. 3, 1966, Ser. No. 541,126
11 Claims. (Cl. 166—9)

ABSTRACT OF THE DISCLOSURE

Residual oil saturations obtained by waterflooding in the presence of a gas phase are lower than those obtained in the absence of gas, and reduction in oil saturation is appreciably more for a water-wet reservoir. It is reasoned that the combination of the two would increase oil recovery. In addition, injection of gas with water tends to improve the mobility ratio and give better areal and vertical sweep efficiency. The injection of gas and water may be alternately done.

The present invention relates to an improved method for the recovery of petroleum from underground deposits thereof. More particularly it is concerned with a secondary recovery method for recovering petroleum from a reservoir thereof wherein the wettability of said reservoir is altered and the oil is produced thereafter by means of injection of a suitable drive agent.

The recovery of petroleum from reservoirs thereof by means of various types of flooding operations have long been regarded as the simplest secondary recovery method to secure good oil displacement efficiencies. One of the principal drawbacks of such procedures, however, has been the large amount of unrecovered oil typical of drives of this kind resulting from low areal and vertical sweep efficiencies and inefficient oil displacement. Generally speaking, the improved recovery methods have larger investment and larger operating cost which have tended to limit the extent of their field application. Currently, improved secondary recovery techniques involve wettability alteration flooding followed by ordinary waterflooding. Thus, after 15-20 percent of the oil in place has been recovered by primary methods, waterflooding usually can account for increasing this recovery up to 30-40 percent. Although the waterflooding process represents a substantial advance over previously practiced methods, many millions of barrels of recoverable oil would be left in the reservoirs if such process represented the ultimate in secondary recovery techniques.

It has previously been recognized that improved oil recoveries over those secured from ordinary waterflooding can be obtained when an oil bearing formation is converted from an oil wet, or neutral wettability condition, to water wet. Recently issued patents by H. R. Froning, U.S. 3,191,676 and 3,203,480, and Canadian 709,209, disclose various additives suitable for use as wettability reversal agents. These patents also teach methods for determining whether a reservoir is oil wet or water wet and disclose the conditions under which wettability reversal agents are used to transform the wettability characteristics of a reservoir rock from oil wet to water wet. In the application of methods of this kind, however, many of the same difficulties arise, from the standpoint of operating efficiency, that are encountered in ordinary waterflooding procedures. For example, where oil is recovered by a wettability reversal method such as disclosed in either of the two abovementioned patents, the flood bank actually has no better displacement and sweep efficiency than is experienced in ordinary waterflooding of a water-

wet reservoir. This means that in the case of reservoirs having their wettability reversed, more oil can be displaced when such step is followed by gas-water injection.

It is an object of my invention to provide a method for recovering oil by employing simultaneously or alternately a combination of wettability alteration and fluid, e.g., gas-water, injection flooding operations. It is another object of my invention to provide a method for obtaining substantially more oil than is possible by the application of a wettability reversal flood alone or a flooding operation using gas-water, or other suitable drive agents. It is a further object of my invention to provide means for improving the sweep efficiency, i.e., the mobility ratio, of a wettability reversal flood by simultaneously or alternately injecting gas into the formation along with the wettability reversal component. It is still another object of my invention to provide a method for the increased recovery of petroleum from an underground deposit thereof by first introducing an aqueous solution having dissolved therein a chemical capable of reversing the wettability of an oil-bearing formation, said solution being accompanied by the simultaneous or alternative injection of gas after which a driving fluid such as water is introduced and which may also be accompanied by simultaneous or alternative injection of gas. It is another object of my invention to provide a means for improving the mobility ratio of a wettability reversal flood bank by introducing into the formation an initial bank or slug of gas prior to injection of the wettability reversal bank.

30 The term "wettability reversal" flooding as used in this description refers to the injection of certain chemicals which act to alter the wettability of a neutral or oil-wet reservoir in the direction of being more water wet. The mechanism involved is to release some of the oil within a rock's pore structure by increasing the rock's surface area actually wet by the wettability agent or the chosen water which is used to drive the chemical bank through the reservoir. While an increased water-wet condition is achieved in a wettability reversal flood on either neutral or oil-wet reservoirs, this merely implies more of the rock is being wet with water. This serves to liberate oil from the rock's pore surfaces and permits more oil to be displaced. While the normal use of wettability reversal flooding is for oil-wet reservoirs, it can be applied just as well to reservoirs of neutral wettability.

In carrying out the process of my invention and after establishing that the reservoir involved is oil wet, as determined by the methods outlined in U.S. 3,028,912 and/or 3,203,480, an aqueous slug of a suitable wettability reversal chemical is introduced into the formation together with a volume of gas. Or if preferred, alternate slugs of the chemical bank and gas may be injected. By this technique the mobility ratio is considerably improved, resulting in improved vertical as well as areal sweep efficiencies of the chemical bank. Alternatively, and particularly where the reservoir has rather wide variations in permeability, it is desirable to inject a slug of gas, i.e., not more than about 10 percent of the pore volume to be flooded, prior to introduction of the chemical bank.

60 Larger volumes of gas have only small effects in obtaining further improvement. Thus, the previously injected gas fills and occupies reservoir pore space thereby causing improved distribution of the chemical solution, bringing about better placement of the bank and improving both the vertical and areal sweep efficiencies thereof.

The chemical bank or solution containing the chemical capable of reversing the wettability of the reservoir rock from oil wet or neutral wettability to water wet is used in volumes of at least about 1 or 2 percent of the pore volume to be flooded or contacted. Volumes as high as 10 percent or more of the conformable pore volume may

be used. However, in the majority of cases, no advantage is to be gained by using total chemical slug volumes in excess of about 10 percent of the pore volume to be contacted. Usually, total chemical slug volumes of from about 2 to 10 percent are preferred. The concentration of chemical or chemicals in this bank likewise may vary. Generally, such concentrations of chemical may range from about 0.05 to about 2.0 molar. As examples of chemicals suitable for converting oil-wet to water-wet formations there may be mentioned the alkali metal sulfides, carbonates, and phosphates, such as sodium sulfide, ammonium sulfide, sodium carbonate, ammonium carbonate, sodium hydrogen phosphate, sodium tripolyphosphate, trisodium phosphate, ammonium phosphate, and ammonium hydrogen phosphate. Other chemicals such as sodium chloride and sodium hydroxide have been used for this purpose and in this connection it is to be understood that the term "wettability reversal chemical," or equivalent designation, as used throughout the present description and claims is intended to refer to the above-named compounds or mixtures of two or more thereof, as well as other such materials used for this purpose and currently known to those skilled in this art.

When the slug of wettability reversal chemical has been placed in the oil-wet or neutral wettability reservoir by introduction through an injection well extending into said reservoir, it is propagated through the formation to the producing well(s), for example, by the simultaneous or alternate injection of gas and water. In terms of hydro-

sodium tripolyphosphate 0.4 molar in carbonate and 0.1 molar in phosphate, is used in Cases 2, 3, and 4, as shown in the table below. In all cases where the solution of wettability reversal chemical was used, it was injected in an amount corresponding to about 5 percent of the conformable pore volume. In Case 1, the saturated core is subjected to ordinary waterflooding until water breakthrough occurs. In Case 2, the solution of wettability chemical is injected until breakthrough after which water is introduced to force the slug of chemical completely through the core until it likewise breaks through. In Case 3, the wettability of the sandstone core is altered from oil wet to water wet by injection of the solution of the wettability reversal chemical until breakthrough thereof and thereafter is followed by natural gas-water (alternate) injection until the latter system breaks through. The gas slugs are approximately 5 percent HPV and the water is injected in amounts of about 10 percent HPV until breakthrough. The last case employs an embodiment of the present invention wherein the oil-wet saturated sandstone core is first injected with alternate slugs of natural gas and ammonium mono-hydrogen, or the phosphate solution, until breakthrough. Next the resulting bank of gas and chemical solution is driven through the core by means of alternate injections of natural gas and water, the total volume of gas and water thus introduced, amounting to about 35 percent of the HPV. The results obtained under these various conditions are set forth in the table below:

carbon pore volume (HPV) the volume of water employed may range from about 1 to 4 volumes per volume of gas. However, beneficial results can be achieved with only small amounts of gas, e.g., 2 percent HPV. When these fluids are injected alternately, the gas should not be injected in amounts in excess of about 5 percent HPV and the water not in excess of about 10 percent HPV. While I ordinarily prefer to use natural gas, others such as flue gas, air, and the like, may be employed. Air is sometimes preferred instead of natural gas, flue gas, etc., because of its relatively low solubility in crude oil. Any gas may be used that is substantially inert with respect to the crude oil and to the well equipment.

The advantages of the process of my invention are further illustrated by the following specific example:

EXAMPLE

Four Torpedo sandstone cores, 8.5 inches by 2 inches are each saturated with a crude oil having a viscosity of 1.4 cps. The resulting oil-wet cores have an initial oil saturation of 90 percent and a connate water saturation of 10 percent. A 0.5 molar solution of wettability reversal chemical, e.g., a mixture of ammonium carbonate and

55 sodium tripolyphosphate 0.4 molar in carbonate and 0.1 molar in phosphate, is used in Cases 2, 3, and 4, as shown in the table below. In all cases where the solution of wettability reversal chemical was used, it was injected in an amount corresponding to about 5 percent of the conformable pore volume. In Case 1, the saturated core is subjected to ordinary waterflooding until water breakthrough occurs. In Case 2, the solution of wettability chemical is injected until breakthrough after which water is introduced to force the slug of chemical completely through the core until it likewise breaks through. In Case 3, the wettability of the sandstone core is altered from oil wet to water wet by injection of the solution of the wettability reversal chemical until breakthrough thereof and thereafter is followed by natural gas-water (alternate) injection until the latter system breaks through. The gas slugs are approximately 5 percent HPV and the water is injected in amounts of about 10 percent HPV until breakthrough. The last case employs an embodiment of the present invention wherein the oil-wet saturated sandstone core is first injected with alternate slugs of natural gas and ammonium mono-hydrogen, or the phosphate solution, until breakthrough. Next the resulting bank of gas and chemical solution is driven through the core by means of alternate injections of natural gas and water, the total volume of gas and water thus introduced, amounting to about 35 percent of the HPV. The results obtained under these various conditions are set forth in the table below.

50 It will likewise be seen that in Case 4, the mobility ratio is more favorable than in any other of the three cases investigated and the flood life is also shorter than any of the other cases when taking into consideration the relatively low injection volume required to complete this flooding operation. Thus, in the waterflood operation (Case 2), it will be noted that while the time required for

breakthrough is slightly more than one-third that required for breakthrough in Case 4, the residual oil saturation in Case 2 is relatively higher, i.e., 29 percent, and the mobility ratio is substantially twice that of the system in Case 4. The flood life of any project is always a very important factor and any means by which this period can be shortened is highly desirable since it is now a fairly well-established rule of thumb that in a flooding project for each year of operation of one injection well and one producing well, the cost is about \$5,000.

It will be apparent that the principle of my invention is applicable to a wide variety of oil-wet and neutral wettability reservoirs to achieve high oil recoveries in a shorter period of time for less operating expense and investment cost than is required by other improved water flooding methods to obtain comparable recoveries. Accordingly, any flooding procedure involving the use of an initial bank of wettability reversal chemical followed by gas-water injection, or the equivalent, wherein the chemical bank is injected before, after, or during the introduction of a gas slug into the reservoir to improve the efficiency of an oil recovery process, is contemplated as lying within the scope of my invention.

The term "reservoir," as used in the present claims is intended to refer only to oil-wet and/or neutral wettability reservoirs.

I claim:

1. In a method for the recovery of petroleum from an oil-wet and/or neutral wettability reservoir thereof having an injection well and a producing well extending into said reservoir wherein an initial bank of a solution of wettability reversal chemical is introduced into said reservoir via said injection well and thereafter propelled through said reservoir toward said producing well by means of a fluid drive agent,

the improvement which comprises introducing a gas into said reservoir via said injection well in conjunction with said chemical.

2. In a method for the recovery of petroleum from an oil-wet and/or neutral wettability reservoir thereof having an injection well and a producing well extending into said reservoir wherein an initial bank of a solution of wettability reversal chemical is introduced into said reservoir via said injection well and thereafter propelled through said reservoir toward said producing well by means of a fluid drive agent,

the improvement which comprises introducing a gas

into said reservoir in the vicinity of said injection well prior to the injection of said initial bank.

3. The method of claim 1 wherein said gas and chemical solution are injected as alternate slugs.

4. The method of claim 1 wherein said gas and chemical solution are injected simultaneously.

5. The method of claim 1 wherein said fluid drive agent is composed of alternate slugs of gas and water.

6. The method of claim 1 wherein said fluid drive agent is composed of gas and water which are injected simultaneously into said reservoir.

7. The method of claim 1 wherein the solution of wettability reversal chemical injected amounts to from about 2 to about 10 percent of the pore volume to be flooded and the gas used in conjunction with said solution amounts to not more than about 20 percent of the pore volume to be flooded.

8. The method of claim 7 wherein the concentration of the chemical in said solution ranges from about 0.1 to about 2.0 molar.

9. The method of claim 8 wherein said chemical is selected from the group consisting of sodium sulfide, ammonium sulfide, ammonium monohydrogen orthophosphate, sodium tripolyphosphate, ammonium di-hydrogen orthophosphate, sodium orthophosphate, sodium monohydrogen orthophosphate, sodium di-hydrogen orthophosphate, sodium pyrophosphate, sodium hydroxide and sodium chloride.

10. The method of claim 7 wherein said fluid drive agent is composed of gas and water in a ratio of about 1:2 to about 1:5, respectively.

11. The method of claim 1 in which gas is injected into said reservoir via said injection well in conjunction with both the initial bank of wettability reversal chemical and 35 with the fluid drive agent.
